UNITED STATES PATENT OFFICE.

EDWARD BRUNHOFF, OF CINCINNATI, OHIO, ASSIGNOR TO H. TRAISER & CO. INC., OF BOSTON, MASSACHUSETTS, A CORPORATION OF MASSACHUSETTS.

CIGAR-DISPLAY HOLDER.

1,076,097.

Specification of Letters Patent.

Patented Oct. 21, 1913.

Application filed March 5, 1913. Serial No. 752,107.

To all whom it may concern:

Be it known that I, EDWARD BRUNHOFF, a citizen of the United States, residing at Cincinnati, in the county of Hamilton and State of Ohio, have invented certain new and useful Improvements in Cigar-Display Holders, of which the following is a specification.

My invention relates to display holder for 10 cigars.

One of its objects is to provide a holder to contain a pair of cigar boxes held at relatively different angles, with separate lids to provide access thereto.

15 Another object is to provide such a holder in which a compartment for a humidifier is provided.

Another object is to provide means to indicate which lid is lifted.

20 My invention also comprises certain details of form, combination and arrangement, all of which will be set forth in the description of the accompanying drawings, in which:

25 Figure 1 is a central vertical section through my improved holder. Fig. 2 is an enlarged sectional detail illustrating the indicating mechanism. Fig. 3 is a perspective view of one of the indicating members 30 detached.

The accompanying drawings represent the preferred embodiment of my invention in which—

A represents a base supporting a frame 35 work B of sheet metal arranged to receive glass panels D in the sides and front end, through which the cigar boxes and their labels are disclosed. The frame work B is so arranged as to hold one of the cigar 40 boxes E in a horizontal position and to hold the other cigar box F above and in rear of the box E and at an angle thereto, so as to display the contents of both boxes to advantage and at the same time. This arrangement of the frame and cigar boxes also provides a triangular space or compartment 45 2 within the frame or holder and between the adjacent faces of the cigar boxes. This space is utilized to contain a humidifier 3, 50 which as illustrated consists of a porous unglazed tile of triangular cross section and extending nearly across the holder, and capable of absorbing a large quantity of water which is given off as a vapor by the extensive surface exposed to keep the atmosphere within the holder uniformly moist. A sheet metal tray 4 is provided for the humidifier to rest upon.

The arrangement of the frame and boxes is such that separate lids 5 and 6 hinged at 5 a common axis serve to cover the respective cigar boxes, said lids being so arranged that only one can be opened at a time by reason of one interfering with the movements of the other. Said lids are provided 65 with glass panels 7 and 8 to expose the contents of the boxes to view. Said lids are preferably hinged together upon a hinge rod 9 which is supported at opposite ends in ears 10 attached to the sides of the frame. 70

In order to support the box F in the desired position, I provide guides 11 and 12 along one side and the rear face of the frame to engage guide and support the lower inclined face of said box. I also provide for 75 turning the lid 15 of the box F backwardly in open position where it is supported by the outwardly turned upper edge 14 of the rear panel of the frame B, so as to expose to view the label on the inside of the lid 15. The lid 80 of the cigar box E is detached before inserting said box into the holder.

On the inside of the frame at one end of the triangular space 2, I provide a gong 17 and a pivotally supported striking lever 85 18 having a striker 19 at one end thereof. At the opposite end the striking lever is shaped into a pawl 20 which engages a curved or segmental bracket 21 attached to one or other of the lids 5 and 6, so as to be 90 engaged by a tooth 22 carried by said segmental bracket to cause the gong to sound whenever the lid carrying said segmental bracket is opened. In practice it is customary to have cigars of different price and 95 grade in the respective cigar boxes, and it frequently happens that the customer opens one of the lids and helps himself to cigars while the store keeper is otherwise engaged. The sounding of the gong notifies the store 100 keeper that the lid above the high priced cigars has been opened, and warns him to examine the goods taken or to collect for the high priced goods.

The apparatus herein illustrated and described is capable of considerable modification without departing from the principle of my invention.

Having described my invention, what I claim is:

1. A cigar box holder comprising a frame having a compartment to hold a cigar box in a substantially horizontal position and a compartment at one side thereof to hold a cigar box at an angle to said first box, and lids hinged to said frame over said respective boxes and opening toward each other. 40
- 10 2. A cigar box holder comprising a frame with transparent panels having a compartment to hold a cigar box in a substantially horizontal position and a compartment at one side thereof to hold a cigar box at an angle to said first box with a triangular compartment between adjacent faces of said respective boxes, lids with transparent panels hinged to said frame to cover and at the same time expose the contents of said boxes 45
- 15 to view. 50
- 20 3. A cigar box holder comprising a frame having a compartment to hold a cigar box in a substantially horizontal position, a compartment at one side thereof to hold a cigar box at an angle to said first box, a compartment to contain a humidor formed between adjacent faces of said respective boxes, lids with transparent panels hinged back to back to said frame to give access to and expose 55
- 25 the contents of said boxes to view. 60
- 30 4. A cigar box holder comprising a frame having a compartment to hold a cigar box in a substantially horizontal position, a compartment at one side thereof to hold a cigar box at an angle to said first box, a triangular 65
- 35

compartment to contain a humidor formed between adjacent faces of said respective boxes, lids with transparent panels hinged back to back to said frame to give access to and expose the contents of said boxes to view, an alarm and means actuated when one of said lids is opened to sound said alarm. 40

5. A cigar box holder comprising a frame with transparent side panels having a compartment to hold a cigar box in a substantially horizontal position, a compartment at one side thereof to hold a cigar box at an angle to said first box, lids with transparent panels hinged to said frame back to back 50 upon a common axis to give access to and expose the contents of said boxes to view. 55

6. A cigar box holder comprising a frame having a compartment to hold a cigar box in a substantially horizontal position and a compartment at one side thereof to hold a cigar box at an angle to said first box, a recess in the wall of said frame through which the cover of one of said cigar boxes projects to display the label on the inner 60 face of said cover, and lids hinged back to back to said frame to fit over said respective cigar boxes. 65

In testimony whereof I have affixed my signature in presence of two witnesses.

EDWARD BRUNHOFF.
